(57) **CLAIM**

The ornamental design for a golf divot tool, as shown and described.

DESCRIPTION

FIG. 1 is a top perspective view of a golf divot tool.

FIG. 2 is a bottom perspective view of the golf divot tool illustrated in FIG. 1.

FIG. 3 is a top plan view of the golf divot tool illustrated in FIG. 1.

FIG. 4 is a bottom plan view of the golf divot tool illustrated in FIG. 1.

FIG. 5 is a left side view of the golf divot tool illustrated in FIG. 1.

FIG. 6 is a right side view of the golf divot tool illustrated in FIG. 1.

FIG. 7 is a rear view of the golf divot tool illustrated in FIG. 1; and,

FIG. 8 is a front view of the golf divot tool illustrated in FIG. 1.

The broken lines in the figures illustrate portions of a golf divot tool and form no part of the claimed design.

1 Claim, 5 Drawing Sheets
